PLASTIC SHEET MATERIAL

John R. Ellefson, Kennett Square, Pa., assignor to E. I.
du Pont de Nemours and Company, Wilmington, Del.,
a corporation of Delaware

Filed Aug. 15, 1961, Ser. No. 66,357

Term of patent 14 years

(Cl. D87—3)

FIG. 1

FIG. 2

FIG. 3

FIG. 4

FIGURE 1 is a plan view of a plastic sheet material showing my new design.

FIGURE 2 is an enlarged view of a portion of the design shown in FIGURE 1.

FIGURE 3 is an enlarged sectional view taken along line 3—3 of FIGURE 2.

FIGURE 4 is an enlarged sectional view taken along line 4—4 of FIGURE 2.

I claim:

The ornamental design for a plastic sheet material substantially as shown.
